UNITED STATES PATENT OFFICE.

CLARENCE H. HOWARD AND HARRY M. PFLAGER, OF ST. LOUIS, MISSOURI, ASSIGNEES
TO COMMONWEALTH STEEL COMPANY, OF ST. LOUIS, MISSOURI, A CORPORATION
OF NEW JERSEY.

CAR-TRUCK.

1,097,634.

Specification of Letters Patent. Patented May 26, 1914.

Application filed September 17, 1912. Serial No. 720,809.

To all whom it may concern:

Be it known that we, CLARENCE H. HOWARD and HARRY M. PFLAGER, citizens of the United States, residing at St. Louis, Missouri, have invented a certain new and useful Improvement in Car-Trucks, of which the following is a full, clear, and exact description, such as will enable others skilled in the art to which it appertains to make and use the same, reference being had to the accompanying drawings, forming part of this specification, in which—

Figure 1 is a top plan view of a four-wheel truck of our improved construction. Fig. 2 is a vertical, longitudinal section taken approximately on the line 2—2 of Fig. 1. Fig. 3 is a transverse section taken approximately on the line 3—3 of Fig. 1. Fig. 4 is a detail section showing a modified 20 form of the swing hanger that supports the spring plank and truck bolster.

Our invention relates generally to improved car trucks of the four-wheel variety, and particularly to a truck designed especially for use beneath locomotive tenders.

The principal feature of our improved construction is the swing hangers utilized for supporting the spring plank and parts carried thereby, which swing hangers have 30 two-point supports, or points of pivotal connection (preferably at their upper ends), the object of which two-point support is to render said hangers comparatively rigid against lateral swinging movement under 35 normal conditions so that on a straight track having an occasional low joint or other low part that might cause the tender body to swing or shift laterally, no swinging movement will be produced, but when the centrifugal force is abnormal, as in rounding 40 curves, the swing hangers will then swing laterally, and, by reason of their two-point suspension, the centrifugal force will be absorbed and utilized as a lifting force for 45 elevating the tender body.

To the above purposes our invention consists in certain novel features of construction and arrangement of parts hereinafter more fully described and claimed.

50 Referring by numerals to the accompanying drawings, 1 designates the wheel pieces and 2 the transoms of the truck frame, said

parts being preferably cast integral so as to provide an especially strong, rigid and comparatively cheap structure. The wheel 55 pieces 1 and transoms 2 are preferably box shape in cross section with suitable gusset plates in the corners between the transoms and wheel pieces. The end portions of the transoms are made substantially narrower 60 than the central portions, such construction being carried out by locating the end portions of the vertical walls of said transoms close to each other, thereby forming comparatively narrow housings for the upper 65 portions of swing links hereinafter described.

Formed in the vertically disposed web plates or walls of the transoms 2 and near the ends thereof are pairs of horizontally 70 disposed bearings 3 in which are seated short, horizontally disposed pins or bolts 4.

The spring plank swing hanger links 5 are provided in their upper ends with short, vertically disposed pairs of slots 6, through 75 which pass the pins or bolts 4. Thus a pair of spring plank swing hangers is arranged adjacent to each wheel piece of the truck frame, and said swing hangers being pivotally supported at their upper ends at two 80 points. The lower portions of the corresponding pairs of swing hangers 5 are connected by horizontally disposed pins or rods 7, and seated thereon are the ends of an ordinary spring plank 8. 85

9 designates a bolster that is preferably formed in a single piece, and which occupies a position between the transoms 2. Interposed between the ends of the spring plank 8 and the end portions of this bolster are 90 the usual elliptic springs 10. Formed on or fixed to the top or central portion of the bolster 9 is a center bearing 11, and arranged on top of the end portions of said bolster are suitable side bearing members 12. 95

The top plates of the transoms 2 are perforated or provided with openings 2^a immediately above the ends of the swing hangers 5, thus permitting free movement of the upper portions of said swing hangers as the 100 same change their positions while in action.

By providing two points of suspension at the upper ends of the swing hangers 5 the truck frame and bolster are maintained com-

paratively rigid against swinging movement under ordinary conditions or while the truck is passing over ordinary straight and level track. In rounding curves where one track rail is comparatively lower than the other or where a low joint or low portion of a rail is encountered, the tendency of the tender body is to shift or swing toward the low side of the truck, thereby bearing downward upon the corresponding end of the truck bolster, which action exerts considerable force toward the low side of the truck, consequently shifting the bolster and spring plank in this direction. The ends of the spring plank are carried between the lower ends of the pairs of swing hangers 5, and consequently the lower ends of said swing hangers will be moved in the direction toward which the force is exerted. The upper ends of the swing hangers are supported by the pairs of pins or rods 4, the members of which pairs are arranged on opposite sides of vertical lines drawn through the centers of the rods 7.

Assuming that the force exerted by the tender body is in the direction indicated by the arrow *a*, Fig. 3, then the lower ends of the links 5 will swing on the arc *b*—*c*, Fig. 3, with the right hand members of the pairs of pins 4 as axes. The relation of these axes to the pins or rods 7 at the lower ends of the swing hangers causes the lower ends of said hangers to rise sharply as said lower ends swing laterally, and, as a result, the corresponding end of the spring plank is elevated, thereby elevating the corresponding end of the bolster, and thus the forces exerted by the shifting body, and which forces tend to depress one end of the bolster, are absorbed by the moving parts just described, and said forces are utilized to lift the depressed ends of the truck and body bolsters with a tendency to right the same and the body supported thereby.

During the swinging movements of the lower ends of the members 5 through the arcs *b*—*c* the right hand members of the pairs of pins 4 serve as pivots for said members, and the latter are free to swing in the manner described relative to the opposite members of the pins or rods 4 by reason of the corresponding slots 6. By thus providing the upper ends of the swing hangers with two points of pivotal connection and arranging these points on opposite sides of vertical lines drawn through the centers of the pins or rods 7, said swing hangers are effective in maintaining the bolsters comparatively rigid against lateral shifting movement under ordinary conditions, and when under abnormal conditions the tender body shifts or swings laterally with a tendency to depress the bolsters, the centrifugal and depressing forces are, through the me-

dium of the swing hangers, exerted as lifting forces upon the depressed ends of the truck bolsters, thereby tending to right said bolsters and the body carried thereby.

In Fig. 4 we have shown a swing hanger provided at its lower end with two points of pivotal connection, which points are arranged on opposite sides of a vertical line drawn through the center of the single point of pivotal connection between said swing hanger and the truck frame, and this construction produces the same lifting effect upon the spring plank and truck bolster wherever said hanger is swung laterally under abnormal conditions.

Swing hangers of our improved construction can be advantageously utilized in connection with all forms of trucks having spring planks and bolsters that are movable with respect to the truck frame.

It will be readily understood that minor changes in the size, form and construction of the various parts of our improved car truck can be made and substituted for those herein shown and described without departing from the spirit of our invention, the scope of which is set forth in the appended claims.

We claim:

1. In a car truck, a truck frame having a pair of transoms which are substantially box-shape in cross section with the end portions substantially narrower than the central portions to form narrow pockets, there being openings formed in the top plates of the transoms above said narrow pockets, swing hangers, the upper ends of which occupy the narrow pockets and the openings in the ends of the transoms, a spring plank supported by said swing hangers, a bolster yieldingly supported upon the spring plank, each of which swing hangers has three points of pivotal connection with the corresponding transom, and spring plank, two of which pivotal points of connection are in horizontal alignment with each other and occupy points equidistant from a vertical line drawn through the axis of the third point of pivotal connection and which swing hangers lie parallel with each other and with the transoms and supported bolster, whereby the latter is held to swing directly at right angles to the axis of the truck.

2. In a car truck the combination with a truck frame having transoms which are substantially box-shape in cross section with the vertical walls at the ends of said transoms arranged comparatively close to each other so as to form narrow transversely disposed pockets at the ends of said transoms, of swing hangers, the upper ends of which occupy the narrow pockets at the ends of the transoms, each of said swing hangers be-

ing provided in its upper portions with a pair of slots, pins seated in the vertical walls of the transoms and passing through the slots in the hangers, a spring plank supported by said swing hangers, and a bolster yieldingly supported on said spring plank.

In testimony whereof we hereunto affix

our signatures in the presence of two witnesses, this 30th day of August, 1912.
